UNITED STATES PATENT OFFICE.

DAVID C. KLAUSMEYER, OF CINCINNATI, OHIO, ASSIGNOR TO THE CINCINNATI BICKFORD TOOL COMPANY, OF CINCINNATI, OHIO, A CORPORATION OF OHIO.

SAFETY-NUT INTERLOCK WITH FEED-CONTROL LEVER.

1,414,327.

Specification of Letters Patent. Patented Apr. 25, 1922.

Application filed November 17, 1920. Serial No. 424,800.

To all whom it may concern:

Be it known that I, DAVID C. KLAUSMEYER, a citizen of the United States, and residing at Cincinnati, in the county of Hamilton 5 and State of Ohio, have invented a new and Improved Safety-Nut Interlock with Feed-Control Lever, of which the following specification is a full disclosure.

This invention deals with safety devices 10 and it proposes a construction such that the user will be compelled to rectify any untoward conditions in the apparatus embodying it before being able to continue the normal use of such apparatus.

15 In various species of machinery, screwing threads are resorted to for the purpose of effecting a translation of certain parts and it is of great importance to prevent the attendant from continuing the use of the 20 mechanism either after such threads have become stripped or destroyed or become weakened by wear until unsafe.

This invention proposes a safety interlock capable of being utilized either in the 25 form shown or in modified form so as to achieve either one or more of the following functions: (1) automatically to expose a normally-concealed part or member as a warning that the threads have become unduly worn, or that they have been destroyed; 30 (2) to interpose a part into the path of a feed or travel control-element to prevent such element from being moved from its inoperative into its operative position; (3) so 35 to co-act with a control-element as to restore it from operative to inoperative position and to retain it in the latter position; (4) to achieve one or more of the above objects while simultaneously providing for a temporary 40 substitute for the threads; and (5) to achieve one or more of said objects while simultaneously holding the part normally actuated by the threads against any further movement whatsoever until a restoration of 45 the damage to the threads has been effected.

It is of importance for an attendant to be advised as to the condition of the threads of a nut that is utilized for sustaining heavy weights or for moving parts against a resili- 50 ent opposition. Machines, as ordinarily constructed, do not give an attendant a sufficient opportunity for observing the condition of such threads and accordingly the attendant is quite likely to continue the use of the apparatus until the threads have become so

weakened as to give way and entail damage. This invention, however, affords a remedy for said condition inasmuch as it provides a part which is normally withheld but which will be released so as to spring into view and 60

serve as a warning that the threads have become so far worn as to make their replacement advisable. Inasmuch as the attendant may fail to observe the warning thus given, and may continue to use the machine until 65

the threads have actually stripped, this invention proposes a safety mechanism adapted to go into operation and prevent any untoward movement of the parts as a result of the stripping of the threads; this feature being combined with the warning device. Furthermore, exigency may demand a temporary usage of the machine even after the 70 regular threads have stripped and this invention accordingly proposes an arrangement which provides a temporarily acting 75

nut in combination with the warning device; the parts being so correlated that the warning device will continue to advise the attendant that the regular threads are out of 80 use and the temporary threads are being employed. This arrangement puts the attendant upon notice that as soon as possible he must effect a replacement of the stripped 85

threads, and yet it permits him to use the machine temporarily. Since, however, the attendant may neglect the warning and may fail to make a thread replacement, this invention proposes, as an additional improvement, an 90

interlock between the warning element and the power feed device; said interlock being of such a nature that it will permit the power feed to continue to function until the attendant has manually disconnected it, but will not 95

permit the attendant thereafter to throw on the power. Whenever it is unnecessary to provide for a temporary continuance in the usage of the machine after a thread-failure, this invention provides an arrangement whereby the power feed shall be ineffective 100

to move the threaded element and yet such element will be retained in the position it occupied at the time of the thread-failure. The cessation in feed will, of course, warn 105

the operator that an immediate repair is essential but inasmuch as he may forget to turn off the power or may erroneously attribute the cessation in feed to a disconnection of the power, and may accordingly attempt to turn it on, this invention provides an arrange- 110

ment in combination with means for arresting all further feed, for throwing off the power if it be on, or preventing it from being turned on if it be off, said arrangement 5 becoming effective simultaneously with any thread yield. So also, the means for preventing the power from being turned on and for automatically turning it off, admits of being arranged in accordance with this disclosure so as to become effective upon a predetermined wear of thread and in advance 10 of the actual destruction of the thread.

Other objects and advantages will be in part indicated in the following description 15 and in part rendered apparent therefrom in connection with the annexed drawings.

To enable others skilled in the art to so fully comprehend the underlying features hereof that they may embody the same in 20 the various ways contemplated by this invention, drawings depicting a preferred typical construction have been annexed as a part of this disclosure, and in such drawings like characters of reference denote corresponding parts throughout all the views, 25 of which:

Fig. 1 is a vertical section through a portion of a machine showing one embodiment of this invention; the parts being in 30 their normal working relation. Fig. 2 is a detail in side elevation showing the separable clutch between a safety element and the regular nut. Fig. 3 is a horizontal section through line 3—3 of Fig. 1 showing 35 the warning element in its retracted or normal position. Figs. 4, 5 and 6 depict a modification corresponding in general with the aforesaid views, respectively, the parts, however, being shown in the position resulting 40 from any undue wear or failure of the threads and showing a rotatable auxiliary nut U. Fig. 7 is a vertical section of a modification of this invention showing means for automatically turning off the 45 power and for positively preventing it from being turned on. Fig. 8 is a detail in side elevation of the engagement normally existing between the nut and the safety element. Fig. 9 is a horizontal section through line 50 9—9 of Fig. 7 showing the parts in their retracted position. Fig. 10 is a detail showing the position occupied by the warning element for positively retaining the power control in its inoperative position.

Continuing now by way of a more detailed description of the embodiments selected for purposes of explanation, it may be stated that this invention is applicable 55 to any apparatus or mechanism wherein a screw cooperates with a nut or its equivalent, i. e., a gear, for the purpose of effecting an approach or separation between two parts or castings such, for example, as the frame-elements A and B. This separation 60 or approach is accomplished against the ex-

istence of some counter tendency such as gravity or heavy spring pressure and it ordinarily is accomplished by effecting a relative rotation between a nut such as C and a screw such as D; the one being suitably mounted against translation relative to the element A, and the other suitably mounted against translation relative to the element B. Thus, the lower end of the nut C is provided with a shoulder 10 interfitting 70 with a counterpart shoulder on the element A and this nut C is secured against rotation by means of a screw 11 in the manner usual in radial drills. The screw D, being used as a lifting-screw, is rotatable and is accordingly journaled at its ends in a stationary part of the machine in any conventional manner, as for example in the manner shown by my United States Patent No. 1,374,581 of April 12, 1921.

In the form illustrated in the drawings, the screw is shown journaled in the member B which is here assumed to be the base or stationary element, and the nut C is nonrotatably secured to the element A which is here illustrated as the movable member. As will be understood, some sort of operating means will be utilized and such means will also be under manual control. For example, the base B may separate the shaft E 95 connected in driving relation with the screw D by means of suitable gears F and this shaft E may be driven either clockwise or counter-clockwise by means of either one or the other of gears G and H which rotate in opposite directions by reason of their connection to the prime-mover J. The connection between the gears G and H with the shaft E may be effected through a suitable clutch, such as the member K, splined 100 to the shaft E and shifted to the right or left by means of an arm L projecting from a member M, here shown in the nature of an elongated vertical bar, adapted to be manually oscillated. For the purpose of facilitating the oscillation of this rod, a hand lever (not shown) may be employed, as will be understood.

Referring to Fig. 1, it will be seen that, in addition to the regular nut C, an auxiliary nut N is threaded to the screw D and that it occupies a position between a shoulder P provided by the frame-element A and the upper end of the regular nut C; there being a clearance space O for the purpose 115 of permitting a predetermined separation between the auxiliary nut N and the regular nut C in the event of undue thread-wear or of thread-failure. It will be perceived that this will happen because the auxiliary nut 120 N normally carries no load; the load being assumed by the regular nut C. Therefore, even though the threads of the regular nut should wear, those of the auxiliary nut N 125 will not be subject to wear since the latter 130

is virtually an idle element. It is essential, however, that these parts shall separate only as a result of thread-wear or failure and not by reason of any relative rotation between them and, accordingly, the auxiliary floating nut N is restrained against rotation by some suitable means such, for example, as the clutch-like engagement Q shown best by Fig. 2. This permits separation without permitting rotation.

A detector for warning the user that an undue separation has taken place is preferably carried by the frame-element A. In the form here shown, this detector assumes the form of a plunger R which is normally restrained against moving under the influence of a spring S by means of an engagement which depends upon the distance between the auxiliary and main nuts N and C. Thus, the plunger R may terminate in an engagement with the auxiliary nut N; said engagement consisting of a shoulder 1 of limited height and normally abutting a side of the slot 2 in the auxiliary nut. If the slide of the shoulder 1 be, say, one-third of the thickness of a thread, the plunger R will be released as soon as one-third of the thread has been worn away. So also, if the thread should strip entirely, the auxiliary nut will immediately be brought to bear against the shoulder P and also the plunger R will be released. If desired, the abnormal position assumed by the plunger R may be depended upon as a warning against a materially extended use of the machine prior to the replacement of the regular nut, or it may be further utilized for the purpose of preventing the movement of the control rod M into its operative position. To this end, the extremity of the plunger R may be shaped, as indicated by T so as to interlock with the rod M or a part carried thereby, as illustrated, for example, by Fig. 6 in case the operating rod M happens to be in its operative position, as shown by the dotted lines in Fig. 6, there will be no interlocking between the extremity of the plunger R and such rod. Consequently, the operator can turn the rod into its operative position and forthwith the plunger will, under the action of the spring S, be thrust into the interfitting relation shown by Fig. 6. The user could only turn on the power when the parts are thus positioned, after the plunger has retreated somewhat, and, to prevent the possibility of any such retreat, the plunger is provided with a shoulder 3 which will be engaged by a detent 4 (pressed by a spring 5) and thereby obstruct any rearward movement of the plunger. To guard against the temptation of manually releasing the detent, it is preferably arranged inaccessible, as shown by the drawings, so that the attendant can restore the parts to their normal position only by going to the trouble of

taking the machine apart to an extent sufficient to effect a replacement of the main nut.

It is to be noted that, in the embodiment shown by Figs. 1 to 3, the temporary nut N will assume the rôle of the regular nut in the event of failure and therefore it must be prevented from turning and hence the tongue and slot connection Q is made sufficiently long so as to continue the engagement after the space O has been eliminated by the movement of the shoulder P against the temporary nut N. As thus constructed, the frame-element A will continue to move under the action of the screw D until the power is turned off by hand. If circumstances render it advisable, the part N can be replaced by a safety collar U threaded to the screw and normally retained against rotating but adapted, in the event of any separation from the nut C, to rotate with the screw and simultaneously assume the weight of the frame-element A. This modification is shown in its effective position by Fig. 4 in which U indicates the safety collar and V indicates a thrust-bearing of the frictionless type interposed between the shoulder P and the collar U so that the collar will be free to rotate by reason of the friction of its engagement with the threads of the screw D. This modification requires an alteration in the proportionment of the tongue and groove connection between the nuts U and C and between the nut U and the plunger R inasmuch as it must permit of an entire separation of the nut U from the nut C and of the plunger R from the path of the tongue Q' so as to enable the collar U to rotate without restraint.

By referring to Figs. 7 to 10 inclusive, there will be seen an adaptation of this invention whereby the power control is thrown off automatically if it be on, and is locked against manipulation if it be off. This arrangement is of a special utility where the auxiliary nut is resorted to since it brings the rotating screw to a standstill and prevents any wearing away of the threads of the auxiliary nut by the chips or débris given off by the main nut when the threads become stripped or torn. In general, the mechanism of this embodiment may follow the constructions hereinbefore described but in order to impart to the plunger R the capacity of throwing off the power, its extremity may be provided with a shoe W having two contact surfaces 6 and 7 which may coact with the fingers 8 and 9 radiating from a dog X adapted to slide along but not rotate relative to the rod M and maintained, by suitable means, such as lugs 12 and 13 projecting from the element A in the same plane as the shoe W throughout the rise and fall of the frame-element A. When the plunger R is released, it will be advanced by the

spring and the appropriate contact surface will impact the appropriate finger to turn the rod M until both of the contact surfaces are in contact with both of the fingers, as shown by Fig. 10, and thereby the power will be disengaged.

Without further analysis the foregoing will so fully reveal the gist of this invention that others can, by applying current knowledge, readily adapt it for various utilizations without omitting certain features that, from the standpoint of the prior art, fairly constitute essential characteristics of the generic or specific aspects of this invention, and therefore such adaptations should be and are intended to be comprehended within the meaning and range of equivalency of the following claims.

Having thus revealed this invention, I claim as new and desire to secure the following combinations of steps and elements, or equivalents thereof, by Letters Patent of the United States:

1. A device of the nature disclosed combining a screw; a load-free member meshing with said screw; a load-carrying member also meshing with said screw and adapted by thread-wear or failure to become varied in distance from said load-free member; means for effecting a relative rotation between said screw and said members simultaneously; and means made operative through a variation in said distance for rendering inoperative said rotation-effecting means.

2. A device of the nature disclosed combining a screw; a load-free member meshing with said screw; a load-carrying member also meshing with said screw and adapted by thread-wear or failure to become varied in distance from said load-free member; means for effecting a relative rotation between said screw and said members simultaneously; and an instrumentality obstructing the utilization of said means, said instrumentality being adapted to become effective through a variation in the distance between said members.

3. A device of the nature disclosed combining a screw; a load-free member meshing with said screw; a load-carrying member also meshing with said screw and adapted by thread-wear or failure to become varied in distance from said load-free member; means for effecting a relative rotation between said screw and said members simultaneously; and a mechanism put into operation through a variation in said distance for automatically holding said rotation-effecting means out of operation.

4. A safety device combining a spring pressed member; means normally retaining said member in retracted position and adapted under abnormal conditions to release it;

and an inaccessible detent adapted automatically to engage said member after it has been advanced by said spring to prevent it from being restored to its initial position.

5. A device of the nature disclosed combining a screw; a member normally connected through a thread-engagement therewith; means for power-driving one of said parts; a manual control for said means; and an instrumentality, rendered effective by movement resulting from undue wear or damage to said thread-engagement, for governing said manual-control.

6. A device of the nature disclosed combining a screw-operated member; a manually operable part for controlling said member; an interponent positionable to obstruct the movement in a given direction of said part; and a detent adapted automatically to retain said interponent in its obstructing position.

7. A device of the nature disclosed combining a screw; two members simultaneously engaging said screw; and a part retained in its normal position by coaction with one of said members; said part being arranged to occupy an abnormal position upon a predetermined variation in the relation between said members due to thread-wear or thread-yield.

8. A device of the nature disclosed combining a rotatable element; two members simultaneously in thread-engagement therewith and simultaneously movable thereby at the same rate, one of said members carrying a load and the other being normally free of load; and a part retained in its normal position by coaction with one of said members, said part being adapted to occupy an abnormal position in consequence of any undue relative movement between said members caused by excess wear or yield of said thread-engagement.

9. A device of the nature disclosed combining a screw; two members in thread-engagement therewith; a spring-pressed element normally latched to one of said members; and a part bodily movable with the other member and carrying said element, whereby a displacement of the one member relatively to the other will effect a release of said element.

10. A device of the nature disclosed combining a screw; two members in thread-engagement therewith; an element coacting with one of said members; a part movable bodily with the other and carrying said element, whereby a relative movement between said members may effect a displacement of said element; and a latch for obstructing a return of said element to its normal position.

11. A device of the nature disclosed combining a screw; a prime-mover therefor;

- means for establishing a connection between said screw and said prime-mover; a manually-controlled part for actuating said means; two members engaging said screw and simultaneously moved thereby, the one carrying a load and the other being load-free; and means effective upon a relative movement between said members for obstructing the manual manipulation of said 5 part.
12. A device of the nature disclosed combining a screw-operated member; a manually-operable part for controlling said member; an interponent positionable to obstruct 10 the movement in a given direction of said part: means cooperating with said interponent for preventing translation of said member whenever said interponent occupies an abnormal position; and a detent adapted 15 automatically to retain said interponent in its obstructing position.
13. A device of the nature disclosed combining a screw; three members simultaneously engaging said screw, two of said members being screw-threaded thereto and the third being nontranslatable associated therewith; and a part retained in its normal position by coaction with one of said members; said part being arranged to occupy 20 an abnormal position upon a predetermined variation in the relation between said members due to thread-wear or thread-yield, one of said threaded members being adapted to obstruct translation of the other threaded 25 member when said part occupies an abnormal position.
14. A device of the nature disclosed combining a rotatable element; a member non-translatably associated with said element; two members simultaneously in thread-engagement with said element and simultaneously movable thereby at the same rate, one of said members carrying a load and the other being normally free of load; a part 30 retained in its normal position by coaction with one of said members, said part being adapted to occupy an abnormal position in consequence of any undue relative movement between said members caused by excess 35 wear or yield of said thread-engagement, said load-free member being adapted to obstruct relative translation between said element and said load-carrying member whenever said part occupies an abnormal position.
15. A device of the nature disclosed combining a screw; a member nontranslatable relative to said screw; two members in thread-engagement with said member; a 40 spring pressed element normally latched to one of said members; and a part bodily movable with the other member and carrying said element, whereby a displacement of the one member relatively to the other will effect 45 a release of said element, the member latched to said element being adapted when unlatched therefrom to obstruct translation of said other threaded member.
16. A device of the nature disclosed combining a screw; a member nontranslatable relative to said screw; two members in thread-engagement with said screw; an element coacting with one of said threaded members; said latter member being adapted to obstruct movement of the screw when said 50 element ceases to coact therewith; a part movable bodily with the other threaded member and carrying said element, whereby a relative movement between said members may effect a displacement of said element; 55 and a latch for obstructing a return of said element to its normal position.
17. A device of the nature disclosed combining a screw; a prime-mover therefor; means for establishing a connection between 60 said screw and said prime-mover; a manually-controlled part for actuating said means; two members engaging said screw and simultaneously moved thereby, the one carrying a load and the other being load-free; the load-free member being adapted to 65 assume a load upon moving relative to said other member; and means effective upon a relative movement between said members for obstructing the manual manipulation of said 70 part.
18. A safety elevating-mechanism combining a stationary member and a member adapted to be raised relatively thereto; a nut mounted in one of said members and normally restrained against rotation relatively thereto; a screw rotatably carried by the other member and threaded through said nut; and means comprising a spring-pressed part normally clutched to said nut, said 75 means being automatically operative under abnormal conditions to release its clutched relation with said nut and enable said nut to rotate as a unit with said screw when said spring-pressed part is de-clutched; whereby 80 the raised member may be supported but not further elevated by said nut notwithstanding a continued rotation of said screw.
19. A safety elevating-mechanism combining an elevatable member and a stationary member; a screw rotatably associated with one of said members; a nut seated in the other member; a spring-pressed part normally clutched to said nut, means normally 85 operative on said nut to prohibit its rotation, 90 said means being automatically adapted under abnormal conditions to permit said nut to rotate as a unit with said screw; and a ball-bearing adapted to receive the thrust between said nut and the member in which 95 it is mounted so as to promote the rotation of said nut when permitted by said means.
20. A safety elevating-mechanism combin-

ing a stationary member and a elevatable member; a nut seated in a socket in one of said members; an anti-friction thrust-bearing interposed between said nut and a shoulder of said socket; a spring-pressed stem 5 translatably mounted in said socketed member; means normally engaging said nut to prevent rotation thereof, said nut and means being adapted automatically to become disengaged under abnormal conditions to permit said nut to rotate freely; and a lifting-screw rotatably connected to the other member and threaded through said nut.

21. An elevating-mechanism combining a member providing a seat, an anti-friction thrust-bearing adjacent said seat; spring-pressed means non-rotatably secured to said member and spaced from said thrust-bearing; a nut intervening between said thrust-bearing and said element and normally clutched to said spring-pressed means; a second member; and a screw rotatably bearing on said second member and extending successively through the bores of said nut and 15 said thrust-bearing and adapted to cooperate with said parts to effect a separation of said members, the construction being such that under abnormal conditions said means and said nut will automatically become de-clutched and said nut will be permitted to ro-

tate as a unit with said screw and thereby render the latter impotent to effect a further separation of said members.

22. A safety elevating-mechanism combining a member having a socket; an anti-friction thrust-bearing shouldered against one end of said socket, a spring-pressed first part non-rotatably and shiftably carried by said member; a tubular second part located in said socket and having its one end adjacent 35 said thrust-bearing and having its other end engaging said first part, one of said parts being adapted under abnormal conditions automatically to shift axially sufficiently to dis-engage the other part and permit the 40 second part to rotate; and a rotatably mounted lifting-screw threaded through said second part and adapted to effect a rotation thereof against said anti-friction bearing when said second part is dis-connected from 45 said first part and thereby render said rotating lifting-screw impotent to feed through said second part.

In witness whereof, I hereunto subscribe my name, as attested by the two subscribing 50 witnesses.

DAVID C. KLAUSMEYER.
